SILENT URINAL

William Bernard Painter, Detroit, Mich.

Application March 9, 1949, Serial No. 80,493

11 Claims. (Cl. 4—139)

1

The present invention relates to a silent urinal. It is an object of the present invention to provide a silent urinal device for toilet seats comprising a tray operable to prevent splashing and to cause urine to be poured quietly into the front portion of the toilet bowl.

It is a further object of the present invention to provide an attachment for a toilet seat movable from operable position to a concealed position beneath the material of the toilet seat.

It is a further object of the present invention to provide a device of the character described comprising a resiliently supported tray forwardly and downwardly inclined and having a front pouring edge.

It is a further object of the present invention to provide a device of the class described for vertically displaceable movement in operative position.

It is a further object of the present invention to provide a tray mounted for movement to concealed position including means for swinging the tray into horizontal position as it is moved to concealed position.

Other objects and features of the invention will become apparent as the description proceeds, especially when taken in conjunction with the accompanying drawings, wherein:

Figure 1 is a plan view of a toilet seat with the invention applied partly in section.

Figure 2 is a fragmentary section on the line 2—2 Figure 1.

Figure 3 is a fragmentary plan view showing the construction of a modified form of the invention.

Figure 4 is a fragmentary vertical section through a modified form of the invention.

Figure 5 is a fragmentary section on the line 5—5 Figure 1, illustrating yet another modified form of the invention.

Referring now to the drawings, the invention is illustrated as applied to a toilet seat 10, the under surface of which is recessed as indicated at 12 and 13 to provide space for receiving the tray and actuating mechanism when in inoperative position.

A tray 14 which may conveniently be formed of sheet metal and which is provided with a rear upstanding flange 15 and upstanding flanges 16 and 17 at the sides thereof, is pivotally supported by a pivot pin 18 to a bracket 19 carried at the free end of a resilient supporting arm 20. Arm 20 is resilient and permits downward deflection of the tray while it is in operative position. The forward end of the tray 21 is not

2

provided with an upstanding flange and constitutes a pouring lip. Preferably the floor or bottom of the tray is longitudinally corrugated as indicated at 22.

5 The resilient supporting arm 20 is pivoted to the under side of the seat by a pivot pin 24 which connects it to an L-shaped bracket 25. A spring 26 is provided normally biasing the arm in a clockwise direction as seen in Figure 1 so as to urge the tray and assembled mechanism into a concealed position within the recess 12 provided at the under side of the seat.

Means are provided for swinging the arm 20 and tray 14 outwardly to the operative position 15 shown in Figure 1. This mechanism may constitute a Bowden wire 28 connected at one end to the arm 20 and having an actuating finger piece 29 at the other end by means of which the tray may be swung to operative position.

20 Conveniently, the Bowden wire may include a finger 30 movable in a slot provided adjacent thereto so that when the finger piece is pulled outwardly to swing the tray to operative position, the parts may be locked in operative position 25 by rotating the finger 30 out of alignment with the slot.

In the operative position illustrated in Figure 2 it will be observed that the tray 14 is downwardly and forwardly inclined. However, for the best utilization of space it is preferred to have the tray horizontal when it is moved to the inoperative or concealed position indicated by dotted lines Figure 1. It is for this purpose that the tray 14 is provided with a pivot connection at the free end of the resilient arm 20.

35 Means are provided which operate automatically to swing the tray into horizontal position as the arm 20 is swung about a vertical axis to position the tray in inoperative or concealed position.

40 The specific mechanism for this purpose may take any one of several forms which are illustrated herein. In the modification illustrated in Figures 1 and 2 a link 32 is provided which is pivoted by a bracket 33 to the under side of the seat. The axis of the pivot connection 34 is spaced somewhat from the pivot pin 24, as is best seen in Figure 1. The inner end 35 of the link 32 is bent and enters an elongated slot 36 provided in the side wall 17 of the tray. In

45 the position shown in Figure 2, downwardly swinging movement of the tray 14 is limited by engagement of the link 32 with the upper surface of the arm 20, these parts being in overlapping relation as is clearly illustrated in Figure 1. The length of the slot 36 is such that

as the arm 20 swings in clockwise direction as seen in Figure 1, the end 35 of the link first moves to the end of the slot 36 away from the pivot connection 18. Further movement of the arm exerts tension on the end of the slot and tends to move the tray 14 into horizontal position.

Instead of employing a straight link as illustrated in Figures 1 and 2, a link 40 may be provided, the remaining parts of the structure all being as illustrated in Figures 1 and 2. The link 40 has an intermediate reversely bent portion 41 and is composed of two legs 42 and 43 angularly disposed with respect to each other. The advantage of this type of link is that the end 35 of the link is thus adapted to exert a resilient yielding pressure on the end of the slot 36 as the tray is swung into inoperative position.

Referring now to Figure 4 there is a somewhat modified construction which differs from that shown in Figures 1 and 2 only in that the side wall 17 of the tray 14 is provided with an inclined slot 45, the inclination of the slot being such that as the headed end 35 of the link 32 moves to the end of the slot 45 away from the pivot pin 18, the tray is caused to assume a horizontal position.

Another modification of the invention is illustrated in Figure 5 which shows a bracket 50 secured to the under side of the recess 12, in the location indicated by dotted lines in Figure 1. The bracket is provided with an inclined camming arm 51 which is adapted to engage the link 32 as the structure approaches limiting concealed position in the recess. The provision of the camming arm 51 serves to elevate the link 32 mechanically and thus to elevate the tray to horizontal position.

Preferably the upper wall of the recess 12 is inclined so that the tray moves into wedging engagement therewith as it approaches concealed position.

It will be observed from Figure 1 that there is thus provided a structure which is adapted to be completely concealed when in inoperative position and yet which is readily moved to operative position by a simple movement of the operating finger piece 29. Moreover, mechanism is provided so that as the tray is swung horizontally between operative and inoperative positions it is also caused to rock about a horizontal axis so as to assume a forwardly and downwardly inclined position when in operative position and a horizontal position when concealed in the recess 12. Obviously, the tray may be designed to incline rearwardly or toward either side and to thus pour toward the rear or either side as desired.

The drawings and the foregoing specification constitute a description of the improved silent urinal in such full, clear, concise and exact terms as to enable any person skilled in the art to practice the invention, the scope of which is indicated by the appended claims.

What I claim as my invention is:

1. An article of the character described comprising a tray having a pouring edge, support means for supporting the tray in a toilet bowl just below the level of the seat and in registry with the opening in the seat, said tray being downwardly inclined toward said pouring edge, said support means comprising a yieldable arm providing for downward displacement of the tray in use, said arm being pivoted at one end to the toilet seat for transverse swinging movement about a vertical axis, and said tray being carried by said arm and movable upon pivoted move-

ment of said arm between an operative position and a concealed position directly beneath the seat.

2. An article of the character described comprising a tray having a pouring edge, support means for supporting the tray in a toilet bowl just below the level of the seat and in registry with the opening in the seat, said tray being downwardly inclined toward said pouring edge, said support means comprising a yieldable arm providing for downward displacement of the tray in use, said arm being pivoted at one end to the toilet seat, the free end of said arm being attached in supporting relationship to said tray, said tray being movable upon pivoted movement of said arm between operative and concealed positions, the under side of the toilet seat being recessed for the reception of said arm and tray.

3. An article of the character described comprising a tray having a pouring edge, support means for supporting the tray in a toilet bowl just below the level of the seat and in registry with the opening in the seat, said tray being downwardly inclined toward said pouring edge, said support means comprising a yieldable arm providing for downward displacement of the tray in use, said arm being pivoted at one end to the toilet seat, and said tray being movable upon pivoted movement of said arm between operative and concealed positions, the under side of the toilet seat being recessed for the reception of said arm and tray, said tray being pivotally secured to the movable end of said arm about a horizontal axis, and means operable upon swinging of said arm to operative position to cause said tray to move to inclined position, and to swing said tray to horizontal position as said arm is swung to inoperative position.

4. An article of the character described comprising a tray having a front pouring edge, support means for supporting said tray in downwardly and forwardly inclined position in a toilet bowl just below the seat and adjacent the front portion of the bowl, said support means comprising a yieldable arm providing for downward displacement of the tray in use, said arm being pivoted at one end to the toilet seat, and said tray being movable upon pivoted movement of said arm between operative and concealed positions, the under side of the toilet seat being recessed for the reception of said arm and tray, said tray being pivotally secured to the movable end of said arm about a horizontal axis, and means operable upon swinging of said arm to operative position to cause said tray to incline downwardly and forwardly, and to swing said tray to horizontal position as said arm is swung to inoperative position.

5. An article of the character described comprising a tray having a front pouring edge, support means for supporting said tray in downwardly and forwardly inclined position in a toilet bowl just below the seat and adjacent the front portion of the bowl, said support means comprising a yieldable arm providing for downward displacement of the tray in use, said arm being pivoted at one end to the toilet seat, and said tray being movable upon pivoted movement of said arm between operative and concealed positions, the under side of the toilet seat being recessed for the reception of said arm and tray, said tray being pivotally secured to the movable end of said arm about a horizontal axis, and means operable upon swinging of said arm to operative position to cause said tray to incline down-

wardly and forwardly, and to swing said tray to horizontal position as said arm is swung to inoperative position, said last means comprising a link pivoted to the toilet seat and having its free end received in a slot in a side of said tray.

6. An article of the character described comprising a tray having a front pouring edge, support means for supporting said tray in downwardly and forwardly inclined position in a toilet bowl just below the seat and adjacent the front portion of the bowl, said support means comprising a yieldable arm providing for downward displacement of the tray in use, said arm being pivoted at one end to the toilet seat, and said tray being movable upon pivoted movement of said arm between operative and concealed positions, the under side of the toilet seat being recessed for the reception of said arm and tray, said tray being pivotally secured to the movable end of said arm about a horizontal axis, and means operable upon swinging of said arm to operative position to cause said tray to incline downwardly and forwardly, and to swing said tray to horizontal position as said arm is swung to inoperative position, said last means comprising a link pivoted to the toilet seat and having its free end received in a slot in a side of said tray, said link being resiliently extensible to resiliently urge said tray to horizontal position as it approaches its concealed position.

7. An article of the character described comprising a tray having a front pouring edge, support means for supporting said tray in downwardly and forwardly inclined position in a toilet bowl just below the seat and adjacent the front portion of the bowl, said support means comprising a yieldable arm providing for downward displacement of the tray in use, said arm being pivoted at one end to the toilet seat, and said tray being movable upon pivoted movement of said arm between operative and concealed positions, the under side of the toilet seat being recessed for the reception of said arm and tray, said tray being pivotally secured to the movable end of said arm about a horizontal axis, and means operable upon swinging of said arm to operative position to cause said tray to incline downwardly and forwardly, and to swing said tray to horizontal position as said arm is swung to inoperative position, said last means comprising a link pivoted to the toilet seat and having its free end received in a slot in a side of said tray, and camming means for raising said link as the tray approaches concealed position.

8. An article of the character described comprising a tray having a front pouring edge, support means for supporting said tray in downwardly and forwardly inclined position in a toilet bowl just below the seat and adjacent the front portion of the bowl, said support means comprising a yieldable arm providing for downward displacement of the tray in use, said arm being pivoted at one end to the toilet seat, and said tray being movable upon pivoted movement of said arm between operative and concealed positions, the under side of the toilet seat being recessed for the reception of said arm and tray, said tray being pivotally secured to the movable end of said arm about a horizontal axis, and means operable upon swinging of said arm to op-

erative position to cause said tray to incline downwardly and forwardly, and to swing said tray to horizontal position as said arm is swung to inoperative position, said last means comprising a link pivoted to the toilet seat and having its free end received in a slot in a side of said tray, said slot being inclined to effect swinging of said tray as aforesaid.

9. An article of the character described comprising a tray having a front pouring edge, support means for supporting said tray in downwardly and forwardly inclined position in a toilet bowl just below the seat and adjacent the front portion of the bowl, said support means comprising a yieldable arm providing for downward displacement of the tray in use, said arm being pivoted at one end to the toilet seat, the free end of said arm being attached in supporting relationship to said tray, said tray being movable upon pivoted movement of said arm between operative and concealed positions, the under side of the toilet seat being recessed for the reception of said arm and tray, resilient means normally retaining said tray in concealed position, and an operator connected thereto for swinging said tray to operative position.

10. An article of the character described comprising a tray having a front pouring edge, support means for supporting said tray in downwardly and forwardly inclined position in a toilet bowl just below the seat and adjacent the front portion of the bowl, said support means comprising a yieldable arm providing for downward displacement of the tray in use, said arm being pivoted at one end to the toilet seat, the free end of said arm being attached in supporting relationship to said tray, said tray being movable upon pivoted movement of said arm between operative and concealed positions, the under side of the toilet seat being recessed for the reception of said arm and tray, resilient means normally retaining said tray in concealed position, and an operator connected thereto for swinging said tray to operative position.

11. A toilet seat having a central opening and recess at its under side open at the inner side of the seat, a supporting arm, pivot means connecting one end of said arm for swinging movement in a plane parallel to said seat, a pouring tray carried by the other end of said arm, said tray being movable upon swinging movement of said arm between a concealed position in said recess and an operative position below the level of said seat and in registry with the opening in the seat.
